UNITED STATES PATENT OFFICE

97,101

DESIGN FOR A CAP FOR THE GAS TANK OF AN AUTOMOBILE

John Sinko, Chicago, Ill.

Application December 12, 1934, Serial No. 54,404

Term of patent 7 years

To all whom it may concern:

Be it known that I, John Sinko, a citizen of the United States, residing at Chicago, Illinois, post office address 351 North Crawford Avenue, Chicago, Illinois, have invented a new, original, and ornamental Design for a Cap for the Gas Tank of an Automobile, of which the following is a specification, reference being had to the accompanying drawing, forming part thereof.

Fig. 1 shows a top plan view of my new design for a cap for the gas tank of an automobile, and Fig. 2 is a side elevation thereof.

The dominant feature of the design is the combination of a frame member and a jewel-like central portion encircled thereby and comprising a decorative reflecting glass of a contrasting color, having relatively small light reflecting formations throughout substantially its entire area.

I claim:

The ornamental design for a cap for the gas tank of an automobile as shown and described.

JOHN SINKO.
